EDWARD F. CHAFFEE, OF SYRACUSE, NEW YORK, ASSIGNOR TO OLIVER M. EDWARDS,
OF SYRACUSE, NEW YORK.

SIDE WEATHER-STRIPPING.

1,116,800.

Specification of Letters Patent.

Patented Nov. 10, 1914.

Application filed May 6, 1912. Serial No. 695,383.

To all whom it may concern:

Be it known that I, EDWARD F. CHAFFEE, of Syracuse, in the county of Onondaga, in the State of New York, have invented a certain new and useful Side Weather-Stripping, of which the following is a specification.

This invention relates to window constructions and has for its object side weather stripping particularly adapted to be used in connection with window frames formed of sheet metal or having sheet metal stops, and it consists in the combinations and constructions hereinafter set forth and claimed.

In describing this invention reference is had to the accompanying drawing in which like characters designate corresponding parts in all the views.

Figure 1 is a fragmentary view showing in elevation a window sash embodying my invention, contiguous portions of the window frame being also shown. Fig. 2 is a sectional view of parts seen in Fig. 1, looking to the left. Fig. 3 is an enlarged cross sectional view on the plane of line "A—A," Fig. 2, parts being omitted. Figs. 4 and 5 are perspective views of the detached members of the weather stripping.

1 is the window sash. 2 is the window frame having inner and outer stops 3, 4, both of which are here illustrated as bent up of sheet metal.

5 and 6, are respectively, the members of the weather stripping, the members being formed of sheet metal and the member 5 being secured to the side edge of the window sash 1 and having an angularly arranged flange 7 lapping one of the faces, as the outer face, of the window sash, this flange 7 tending to stiffen the member 5 so that the major portion thereof, through which fastening screws 8 are passed into the window sash, will not be bent inwardly at the points that the heads of the screws bear against the sash, as will be understood by those skilled in the art. Said flange 7 also forms a bearing surface for engaging the metal stop 4. The major part of the member 5 closes one side of a rabbet 9 formed in the window sash, and opening through the edge of the sash and through one of the faces thereof, as the inner face.

The member 6 of the weather stripping is associated with one of the stops, as the stop

3, and is preferably separable therefrom, that is, not formed integral therewith, and said member is bent up of sheet metal and is formed with a base 10 adapted to be inserted under, and held in position by, one of the window stops, as 3, the base being here shown as bent U-shape to form a channel 11 facing in the direction of the plane of the window, that is, inwardly toward the center of the window, and with a flange 12 for entering the rabbet 9, the flange projecting from the free edge of one of the walls of the channel, so that it is offset from the opposing surface of the window frame.

The window stop 3 is preferably bent up of sheet metal and as clearly seen in Fig. 3, a portion thereof is formed U-shape in general outline and one of the side flanges as 13 of the U-shape formation extends into and fits the channel 11 and serves to hold or clamp the member 6 in position, the stop 3 being held in position by suitable clamping members as screws 14.

The window casings of cars are usually constructed with the sheet metal stops 3, 4 and are adapted to receive various window sashes, and by my construction of weather stripping, the member 6 associated with the frame can be readily attached to standard casings without special forms of stops or without boring holes in the frame for attaching such weather stripping member in position.

The window sash 1 is pressed toward the outer stop 4 by suitable devices 15 and is provided with suitable fixtures 16 by which it can be raised and lowered and held in an elevated position.

What I claim is:

1. The combination with a sash frame and a sash slidably mounted therein and provided along one edge with a channel opening out through the face of the sash, of a sheet metal weather-stripping member including a doubled part extending in a direction parallel to the face of the sash and having its doubled edge resting against the sash frame, and a flange extending at right angles from the outer edge of one of the legs of the doubled part and operating within said channel in the sash, and means for holding said member rigidly in place.

2. The combination with a window frame and a sash slidably mounted therein and

- provided with a channel opening out through its front face, of a sheet metal weather-stripping member comprising two parts disclosed at right-angles to each other, 5 one of the parts resting at one edge against a window frame and having a channel opening out through its opposite edge, and the other part extending from the last named edge and slidably coöperating with the channel in the window sash, and means for retaining the member in place.
3. The combination with a sash frame and a sash slidably mounted therein, and provided with a channel at one edge opening 15 out through the face of the sash, of a weather-stripping member including a base and a flange disposed at right-angles to each other, the base being doubled upon itself and resting at one edge against a surface 20 fixed in respect to the sash frame, and the flange extending from the opposite edge of the base and projecting within the channel in the sash, and a rigidly retained sash stop with a front wall arranged parallel to the 25 face of the sash and having the inner edge portion thereof extending between the doubled portions of the weather-stripping member for rigidly retaining the same in place.
4. The combination with a sash frame and 30 a sash having a channel opening out through the front face thereof, of a weather-stripping member including two parts disposed at right-angles to each other, one of the parts extending into the channel in the sash, 35 and the other part resting against the sash frame and having a channel opening out through its edge from which the other part extends, a front window stop having a part projecting into the last-named channel, and 40 means for rigidly securing the stop to the frame and retaining the weather-stripping member in place.
5. The combination with a sash frame and a sash slidably mounted therein and having 45 at one edge a vertical channel opening out through the front face of the sash, of a sheet metal front stop having inner and outer walls arranged substantially parallel to the face of the sash and having their 50 edges resting against fixed surfaces, and a connecting wall spaced apart from the plane of said fixed surfaces, a retaining member extending through the last named wall and engaging the sash frame for rigidly holding 55 the stop in position, and a flange rigid with the front wall of the stop and extending perpendicularly from an intermediate

part of said wall and projecting within the channel in the sash.

6. The combination with a sash frame, of 60 a sash having a rabbeted lengthwise edge with one wall of the rabbet intersecting the front face of the sash and the other wall the adjacent end edge of the sash, an angle-plate secured to the edge of the sash and 65 having a leg coöperating with a rear window stop, and a second leg resting against the end edge of the sash, and having a portion extending beyond the second-named wall of the rabbet and opposing the first- 70 named wall of the rabbet and forming therewith the side walls of a channel, a rear window stop, and a front stop having an inner wall extending in parallelism with the front face of the sash, and a flange supported by 75 said wall and extending perpendicularly from an intermediate part of the same and projecting in between said walls of the channel in the sash, and a fastening member passing through the front stop and into the 80 sash frame for rigidly holding the stop and flange associated therewith in operative positions.

7. In a window structure and in combination, a window frame, a window sash, a metallic rear stop having a forwardly extending part resting directly against the window frame, a front metallic stop having a wall arranged parallel to the face of the sash, a weather-stripping member secured to an 90 edge of the sash, and a stationary weather-stripping member comprising a flange portion coöperating with the sash and the first-named weather-stripping member, and a base portion disposed at right-angles to the 95 flange portion, and comprising two legs constituting the side walls of a channel, said wall of the front stop having an edge portion projecting between said legs, and a fastening member extending through the front 100 stop, the forwardly extending part of the rear stop, and into the window frame for holding the parts in place, substantially as and for the purpose described.

In testimony whereof, I have hereunto 105 signed my name in the presence of two attesting witnesses, at Syracuse, in the county of Onondaga, in the State of New York, this 2nd day of May, 1912.

EDWARD F. CHAFFEE.

Witnesses:

L. M. DAVIS,
CHAS. F. YOUNG.

It is hereby certified that in Letters Patent No. 1,116,800, granted November 10, 1914, upon the application of Edward F. Chaffee, of Syracuse, New York, for an improvement in "Side Weather-Stripping," an error appears in the printed specification requiring correction as follows: Page 2, line 4, for the word "disclosed" read *disposed*; and that the said Letters Patent should be read with this correction therein that the same may conform to the record of the case in the Patent Office.

Signed and sealed this 1st day of December, A. D., 1914.

[SEAL.]

R. F. WHITEHEAD,
Acting Commissioner of Patents.
